SLIDING DOOR CONSTRUCTION

Roy W. Tadd, San Gabriel, Calif.

Application December 8, 1950, Serial No. 199,885

1 Claim. (Cl. 20—19)

1

This invention relates to the construction of sliding doors and is more particularly directed to sliding doors enclosing a shower.

In present shower-enclosing sliding door structures, it has been found that there is shower spray leakage between the outer ends of the doors and the walls against which these door ends are intended to abut. Since the doors are conventionally of the type that are suspended by means of rollers from an overhead track, they are quite free and it is difficult to so hang them as to achieve non-leaking engagement with said walls. This condition is aggravated by the unlikelihood of said walls being straight, true and parallel. Hence, even when the doors are manually slid into firm abutment with the walls, a space results from misalignment, from a bow or bulge in either the walls or the door edges, or because the doors slip back on the track. Merely providing compressible sealing strips along said door edges would not solve this problem, since the elasticity of such strips would cause retraction or spring-back of the freely suspended easy-rolling doors and leakage spaces would result.

Accordingly, an object of the present invention is to provide novel and improved means to hold the sliding doors of a shower enclosure closed against the elasticity of sealing strips along the wall-abutting ends of the doors to thereby properly seal against shower spray.

Another object of the invention is to provide sealing strips for the outer ends of shower-enclosing doors that readily conform to unevenness or misalignment of the walls or jambs abutted by said door ends, the strips being so formed that considerable spring-back of the doors may occur and yet effective water sealing is obtained.

It is advantageous that constructions of this type be easily and quickly installed, that the doors be interchangeable, and that the components of the doors be of stock size.

It is another object of the invention, therefore, to provide a sliding door structure that is so constructed that the same can be assembled and disassembled as a unit, in which the doors can be interchanged outside to inside according to the position of the shower head or heads, and in which the width dimension of the completed structure is not critical because of the inclusion of flap type sealing strips that have a wide range of sealing positions.

Another object of the invention is to provide guide means for the lower ends of the freely suspended sliding doors, the same contemplating both non-frictional guiding of the doors and effective leakage sealing along the top edge of the wall of the tub above which the present structure is mounted.

The invention also has for its objects to provide such means that are positive in operation, convenient in use, easily installed in a working

2

position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is an elevational view, as seen from the inside or tub side, of a sliding door structure according to the present invention.

Fig. 2 is a fragmentary and enlarged plan view of one end of said structure.

Fig. 3 is a vertical sectional view taken on line 3—3 of Fig. 2.

Fig. 4 is a further enlarged fragmentary plan view of sealing means employed in the invention.

Fig. 5 is a similarly enlarged cross-sectional view taken on line 5—5 of Fig. 1.

Fig. 6 is a fragmentary side view of a lower corner of one of the doors of the structure.

The present door structure is framed by side walls or jambs 10 and is disposed above and upon the top of a tub 11. Said jambs and tub are generally conventional.

The present structure comprises, generally, upper support track means 12, supported by and spanning between walls 10, two doors 13 and 14 suspended from the means 12, lower door-guiding means 15 disposed on tub wall 11, water-sealing means 16 carried by each door along the outer edge thereof for sealing engagement with walls 10, and friction door-holding means 17, carried by the track means, and engageable with the doors to retain the latter against spring-back movement when the doors are moved to closed position, as shown in Fig. 1.

The support track means 12 comprises a track beam 18 and a pair of brackets 19 that removably support the beam and are affixed to walls 10. Front and back flanges 20 on each bracket define a socket receptive of the ends of said beam, and lugs 21 on each bracket engage the upper wall 22 of said beam to support the same.

It will be clear, therefore, that the beam 18 is not fixed in place but rather is supported by the brackets 19 and can be removed by upwardly lifting the same from engagement with the brackets. Centrally of the side walls 23 of the beam there is provided an intermediate and parallel wall 24, said three latter walls being provided with tracks 25 to form two longitudinal side-by-side trackways, one for each of the doors 13 and 14. Beam walls 23 are deeper than wall 24 so that they overhang the upper portions of the doors, as best seen in Fig. 3.

Each door 13 and 14 comprises a frame 27, a suitable transparent or translucent panel 28 set in said frame, and sealing-gaskets 29 that seal around said panels. Typical of sliding doors, the width of the present doors is such that, when in closed position, there is an overlap of the inner or adjacent ends of the doors. The bottom of each door, on the sides adjacent each other, is provided with a downwardly-reaching flange 30 that comprises a leg of an angle member secured to the bottom edge of each said door. In a conventional manner, the doors are provided on both sides with handles 31, and one door, preferably the outer door 14, on the tub side thereof, is provided with a bumper 32 to prevent each door from encountering the handles of the other.

The lower door-guiding means 15 comprises a track rail 33 that is provided with parallel tracks 34 that are vertically aligned with trackways 26 in beam 18, said tracks being receptive of flanges 30, as shown in Fig. 5. Side walls 35 and an intermediate wall 36 are formed to have laterally directed lips 37 that define tracks 34. Flanges 30 and track rail 33 are conventionally made of metal. In order to obviate a metal-to-metal engagement of these parts, the flanges, at two spaced points, are provided with non-metallic blocks or pads 38 that have a thickness slightly smaller than the width of tracks 34. Said blocks are advantageously made of a phenolic resin-imregnated fabric of the type called "micarta." The doors are, thereby, guided against undue sway on their suspension means and, also, the plating usually applied to track rails 33 is not scratched by the doors because of blocks 38. Said blocks are made in H-form, the webs of which fit into notches formed by flanges 30.

The underside of track rail 33 is formed to have a longitudinal seat or recess 40 and within said recess there is positioned a strip of sealing rubber 41 that is cemented only at 42 on the outer side of the rail, the inwardly directed portion being free to rest upon the top edge of the tub wall 11 to intercept moisture from within the enclosure. Thus, the track rail may rest directly on said tub wall and the sealing flap is completely hidden from view.

The sealing means 16 on each door 13 and 14 comprises a generally U-shaped strip of rubber 42, one leg 43 of which is clamped to the door edge by a metal strip of molding 44, and the other leg 45 of which is somewhat longer and constitutes a resilient flap that has flat engagement with wall 16 to seal thereagainst. Flap 45 seeks an angular position but, when pressed against wall 16, flattens thereagainst to effect moisture sealing by accommodating itself to any unevenness there may be in said wall. It is preferred to apply strips 42 so that the edges of flaps 45 are directed toward the tub side of the structure. It will be clear that this sealing means or any sealing means that has yieldability or compressibility will cause retraction or spring-back of the doors that would nullify the seal; the means 17 is provided to constitute a friction lock that counteracts such retraction or spring-back.

The means 17 is here shown as a length of spring wire 46 that has a rounded leading end 47 and is located slightly below the under face of top wall 22 of track beam 18 in that trackway 26 in which the door to be held moves. A bracket 48 (one of two such brackets), fastened to the top edge of the door and mounting the rollers 49 that ride tracks 25, has a top face 50 that

encounters wire 46, and frictionally engages the same, as illustrated in Fig. 3.

Latch wire can only resiliently move in a vertical plane, being guided in a groove 51 formed in top wall 22 of the track beam. An eye 52 formed on said wire for a bolt 53 that passes through slot 54, is adjustably held to position the free end of the wire where desired to effect friction-locking engagement with the bracket face 50. Since, normally, wire 46 is slightly angularly directed, the same is upwardly flexed in locking position. The tightness of the lock can be adjusted by sliding means 17 along the groove 51.

One such lock is provided for each door. Since greater flexibility of installation is afforded thereby, both ends of wall 22, above each trackway, are provided with slots 54. In this manner, depending on which side the shower head is disposed and to obviate leakage where the doors overlap, said doors can be transposed, inside for outside, and there is available a slot 54 for lock means 17.

While the invention that has been illustrated and described is now regarded as the preferred embodiment, the construction is, of course, subject to modifications without departing from the spirit and scope of the invention. It is therefore not desired to restrict the invention to the particular form of construction illustrated and described, but to cover all modifications that may fall within the scope of the appended claim.

Having thus described the invention, what is claimed and desired to be secured by Letters Patent is:

In a sliding door construction having an upper track beam and two sliding overlapping doors suspended from said beam and each door movable to close an opening between opposite abutment walls, there being a compressible resilient sealing strip between each said wall and the door abutting thereagainst, the improvement that comprises two resilient elements secured to said beam, one adjacent each end thereof and each element aligned with each respective door, each door being provided with a member above the top thereof and extending upwardly into interfering relation with the respective resilient element to frictionally engage said element to hold said door against retractive movement induced by the force of expansion in the sealing strip when compressed between the door and the wall abutted thereby, said track beam at each end being formed with an elongated slot, each resilient element comprising a length of spring wire disposed within and, in part, below each respective slot, and an adjustable fastening connecting one end of each said wire to the track beam.
